ATTORNEY

UNITED STATES PATENT OFFICE.

ETHAN N. HESCOCK, OF WESTFIELD, NEW JERSEY, AND ERNEST F. SMITH, OF WOODHAVEN, NEW YORK, ASSIGNORS TO NEW JERSEY FOUNDRY AND MACHINE COMPANY, A CORPORATION OF NEW JERSEY.

PORTABLE ELEVATOR.

1,344,271.

Specification of Letters Patent. Patented June 22, 1920.

Application filed September 20, 1918. Serial No. 254,895.

To all whom it may concern:

Be it known that we, ETHAN N. HESCOCK, a citizen of the United States, and a resident of Westfield, in the county of Union and State of New Jersey, and ERNEST F. SMITH, a citizen of the United States, and a resident of Woodhaven, in the county of Queens and State of New York, have jointly invented a new and useful Improvement 10 in Portable Elevators, of which the following is a specification.

Our invention relates to portable elevators which are used to stack bags, bales, boxes, barrels, rolls, bundles, textiles, 15 leather, tobacco, or any material. Such portable elevators are moved from place to place on the floor of the wharf, warehouse, factory or other building where it is desirable to stack the material.

20 For the purpose of more readily describing our invention we have shown it in connection with the accompanying drawing, in which the same reference numerals refer to similar parts in the several figures.

25 Figure 1 is a side elevation of our portable elevator showing the platform elevated.

Fig. 2 is a horizontal section, substantially on the line 2—2 of Fig. 1 looking in 30 the direction of the arrows.

Fig. 3 is a fragmentary side elevation on a large scale, partly broken away.

Fig. 4 is a rear elevation partly broken away, and certain elements being omitted 35 for clearer illustration.

Fig. 5 is a rear elevation, similar to Fig. 4, but showing the additional supporting members in their operative position.

Fig. 6 is an enlarged detail view of the 40 friction disk type of brake preferably employed with its connections;

Fig. 7 is a detail view of the pawl.

To more readily turn and maneuver such portable elevators it is the common practice to support them on three traction wheels 45 of which one is swiveled. The arrangement usually employed is to have two wheels mounted to support one end of the portable elevator, the other end of the elevator, being supported by the swivel wheel, which is usually mounted in alignment with the longitudinal axis of the elevator.

While this arrangement of supporting

wheels has many advantages permitting easy manipulation of the portable elevator 55 upon the floor of the warehouse or other location wherever it is used it has the disadvantage of making the elevator unstable. When the platform of the elevator is raised, as shown for example in Fig. 1, 60 a careless operator is apt to make the platform wobble or move at an angle to the longitudinal axis of the elevator.

A slight transverse movement of the elevator frame near the supporting wheels, 65 will be accentuated on the elevator platform when in its raised position. A careless operator might cause the load 1 to fall from the platform 2, or the operator himself might slip or fall from the unstable 70 platform.

By our invention we insure that the platform 2 will always be stable even though the elevator has but three traction wheels, 75 as shown in the drawing. Further, to insure against accidents, we arrange our invention so that the platform 2 cannot be elevated without first moving into operative position the additional safety supporting means.

We have shown our invention in connection with the portable elevator having the frame 4, traction wheels 5, and a swivel traction wheel 6 pivoted at 7 on the support 8. The elevator is provided with a vertical 85 support or guide 9 upon which moves the platform 2 by operating the rope, or other flexible connection 10 one end of which is secured at 11 to the platform 2 and then passes around the pulley 12 to the winding 90 drum 13. This winding drum is operated by a crank 14, and pinions 15, 16, 17, and 18. The drum 13 is mounted upon the same axle 19 as is the pinion 18. The hoisting mechanism is also provided with a brake 20. 95 The hoisting mechanism, so far described, is no part of our invention as any suitable hoisting mechanism may be used. The brake 20 is preferably of the Weston friction disk type. The platform 2 and load 1 100 are held automatically in any position and are controlled by the hand-crank 14. Releasing pressure on this crank 14 locks disk brake 20 in the manner well understood in the art.

105 We have shown in Fig. 6 one type of fric-

tion brake disk which we preferably employ. The brake wheel 20 is provided on its periphery with ratchet teeth 21 which engage with a pawl 51 pivotally mounted on the bushing 52 carried by the frame 53. This brake wheel 20 is loosely mounted on the axle 54 which is carried by the frame 53 and 55.

Fast on this axle 54 is mounted the gear 10 wheel 16. Secured also to this axle is the collar 56 as by means of the pin 57. This collar has cams 58, 58 which engage with the coöperating cams 59, 59 carried by the loosely mounted gear wheel 17. This gear 15 wheel 17, on the side opposite from the cams, has a friction hub or surface 60 which is fast to it.

On the opposite side of the brake wheel 20, we mount a collar 61 held fast on the 20 axle 54 by means of the pin 62. The brake wheel 20 is preferably cut away or recessed to receive loosely mounted friction disks 63, 63 one on each side of the brake wheel 20.

25 In raising a load by operating the crank 14, the gear 16 is caused to rotate and with it the axle 54 and collar 56. The shoulders of the cams 58, 58 on the collar 56 and the shoulders of the cams 59, 59 on the loose gear wheel 17 will engage and cause this gear wheel to rotate with the shaft 54 and hence transmit power to the gear wheel 18 to operate the drum 13. In this operation the slight friction of the collar 61 and friction hub 60 and friction disks 63, 63 will cause the brake wheel 20 to rotate idly under the pawl 51.

When the power is released from the 40 crank 14 the action is then automatically reversed. The load then tends to operate the brake mechanism and connections just described. The load, in seeking to fall, will reverse the rotation of the gear 18 which in turn will reverse the direction of rotation of the loose gear wheel 17. This will cause the 45 cams 58, 58 and 59, 59 to move slightly on each other as shown in Fig. 6. This action causes the loose gear wheel 17, with its friction hub or surface 60 to move slightly to the right of Fig. 6 and carry with it the 50 loose brake wheel 20. This lateral movement is arrested by the friction collar 61 fast on the shaft 54. Further rotation, or attempted rotation in this direction, of the 55 gear wheels 18 and 17 will be prevented by the pawl 51 engaging with the teeth 50 of the brake wheel 20 preventing further retrograde movement of the gear wheels 17 and 18. The load will therefore be held automatically in its elevated position.

60 To lower the platform or load it is only necessary to control the crank 14 so as to control the cams 58, 58 and 59, 59. By operating the crank in the proper manner 65 sufficient pressure is thrown upon the fric-

tion surfaces 60 and 61 and brake disks 63, 63 so that the gears 17 and 18 will be permitted, under control, to lower the platform or load. During this operation the brake wheel 20 is held from rotation by 70 the pawl 51 and is clamped more or less firmly by the rotating friction members 60, 61 and disks 63, 63. Upon again operating the crank 14 to raise the platform or load the brake wheel 20 will again rotate under 75 the pawl 51.

We have shown our improvement coöperating with a movable part of the hoisting mechanism so that the platform 2 cannot be raised without our safety attachment, being first brought into operative position. For purposes of illustration we have shown our improvement coöperating with the brake. We provide the periphery of the 80 brake 20 with ratchet teeth 21. On the strut 22 of the frame we mount a support 23 upon which is pivoted a lever 24 having ratchet teeth 25—25 which are adapted to coöperate with the teeth 21 on the brake when the device is in its inoperative position as shown 90 in Fig. 4. Upon the lever 24 and upon the same pivot 26 we pivotally mount the supplemental safety supporting means which in the form shown are legs which pass through slightly enlarged openings 29—29 95 in the cross piece 30 of the frame.

When it is desired to move the portable elevator, by pulling it around by the handle 32, the lever 24 is raised to remove the ends of the legs 28—28 from contact with the floor. This, however, will bring the teeth 25—25 on the lever 24 into contact with the 100 teeth 21 on the brake of the hoisting mechanism. To keep the parts in this position we mount a plate 33 on the frame so that the lever 24 rests on the top of it when the parts are as shown in Fig. 4.

After the elevator has been brought into its new position, ready to stack other articles, it is impossible to operate the hoisting 110 mechanism to raise the platform 2 as long as the ratchet teeth on the lever 24 are in engagement with the teeth 21 upon the brake of the hoisting mechanism. This will require that the operator, however careless he 115 may be, first release the lever 24 from engagement with the teeth 21. In doing this however, he will automatically force the ends of the legs 28—28 into contact with the floor which insures that the elevator frame 120 will be supported at its four corners, in addition to the support of the swivel wheel 6. This gives a firm and rigid support for the elevator and prevents the tipping or wabbling of the platform 2 which often leads to 125 serious results.

The pressure of the legs is such that they do not cut or mar the floor. To insure the legs 28—28 being held on the floor the lever 24 is provided with a tooth 35 which co- 130

operates with one of the teeth 36 of the plate 33.

The particular form of additional supporting means shown by way of example, 5 but to which our invention is, of course, not to be confined, includes the supporting legs and the means to operate them.

Having thus described this invention in connection with an illustrative embodiment 10 thereof to the details of which I do not desire to be limited, what is claimed as new and what it is desired to secure by Letters Patent is set forth in the appended claims.

What I claim as my invention and desire 15 to secure by Letters Patent is:—

1. In portable elevators the combination of a movable elevator, means to support said elevator on the floor, hoist mechanism, vertically movable additional supporting members, 20 means to control the movement of said members said means adapted to coöperate with the hoist mechanism to lock and release the hoist mechanism.

2. In portable elevators the combination 25 of a movable elevator, means to support said elevator on the floor, hoist mechanism, vertically movable additional supporting members, means to control the movement of said 30 members said means coöperating with and locking the hoist mechanism in the inoperative position of the additional supporting members.

3. In portable elevators the combination 35 of a movable elevator, traction wheels supporting the elevator in an unstable condition, and means carried by the elevator and adapted to coöperate with the hoisting mechanism to securely support the elevator in a

stable condition and to lock and release the hoist mechanism.

4. In portable elevators the combination 40 of a movable elevator, traction wheels supporting the elevator in an unstable condition, and means carried by the elevator and coöoperating with and locking the hoisting mechanism in its inoperative position and in its operative position adapted to secure and support the elevator in a stable condition.

5. In portable elevators the combination 45 of a movable elevator, means to support said elevator on the floor, hoist mechanism, and additional supporting means coöoperating to lock and release the hoist mechanism.

6. In a portable elevator the combination 50 of a movable elevator having three supporting wheels, hoisting mechanism, and additional supporting means interlocking in its inoperative position with the hoisting mechanism, and in its operative position engaging the floor or ground.

7. In a portable elevator the combination 55 of a movable elevator, means to support said elevator on the floor, a hoist mechanism including a brake and clutch and additional supporting means adapted in its inoperative position to coöperate with the brake and clutch to prevent the operation of the hoist mechanism, and in its operative position to support the movable elevator in a stable condition.
